UNITED STATES PATENT OFFICE.

JOHN C. BOHMKER, OF BRADLEY, ILLINOIS, ASSIGNOR TO SEARS, ROEBUCK AND COMPANY, OF CHICAGO, ILLINOIS, A CORPORATION OF NEW YORK.

MOWER.

1,254,879.

Specification of Letters Patent. Patented Jan. 29, 1918.

Application filed March 14, 1917. Serial No. 154,665.

To all whom it may concern:

Be it known that I, JOHN C. BOHMKER, a citizen of the United States, residing at Bradley, in the county of Kankakee and State of Illinois, have invented certain new and useful Improvements in Mowers, of which the following is a specification.

This invention relates to improvements upon mowers of the type having a main or primary framework to which the tongue and the seat support are rigidly attached, and a secondary frame pivotally connected to the main or primary frame, the finger bar being hinged to the secondary frame.

15 Among the objects of the invention are to provide improved means for raising and lowering the finger bar, to provide an improved manner of supporting the yoke to which the finger bar is pivoted, and to provide an improved arrangement of the secondary frame whereby increased traction is obtained.

In the accompanying drawings, Figure 1 is a fragmentary side elevation of a mower embodying the features of my invention. Fig. 2 is a fragmental front elevation of the mechanism for lifting the finger bar. Fig. 3 is a section through the tongue. Fig. 4 is a fragmental plan view of the machine.

30 In the drawing, the main or primary frame is indicated at 1, said frame comprising a tubular portion or sleeve 2 through which the axle 4 extends. 5 denotes one of the drive wheels. The tongue 1^a and the seat support (not shown) are rigidly attached to the main frame 1. The secondary frame consists of three bars 6, 7 and 8. The stubbleward end of the front bar 6 has a ball-and-socket connection at 9 with the main frame 1. The opposite end portion of the front bar 6 is rigidly connected to the forward end of the push bar 7 by means of a bracket or casting 10. The rear end of the push bar 7 is pivoted at 11 to an arm 12 which is rigid with the tubular portion 2 of the main frame and projects downwardly from said tubular portion. The bar 8 is rigidly secured to the bars 6 and 7 by means of the brackets 13 and 14 and serves to brace the secondary frame. Any ordinary or suitable means may be provided for raising the secondary frame to lift the cutting mechanism off the ground when desired.

A yoke 15 is pivotally mounted upon the

grassward end of the bar 6, said yoke having a front arm 15^a and a rear arm 15^b that serve pivotally to support the shoe 16 for the finger bar 16^a. As shown in Fig. 4, the sleeve 17 of the yoke has an aperture 18 therein through which the bracket 10 projects. By thus forming an opening in the sleeve 17, it becomes possible to locate the bracket 10 close to the extreme end of the bar 6, whereby the bar 6 is effectively supported against bending stresses, and great strength is obtained. The stubbleward end of the sleeve 17 lies between the brackets 10 and 14.

The means for raising and lowering the finger bar comprises an arm 19 fixed to and extending upwardly from the shoe 16 at a point forward of the front arm 15^a of the yoke 15. The upper end of said arm is connected by means of a chain or other suitable flexible connection 20 to a winding segment 21 which is pivoted upon the forward end of the brace bar 8 in front of the front bar 6. The segment 21 extends toward the shoe 16. When the finger bar is being raised, the chain 20 is pulled down under the segment 21. As best shown in Fig. 2, the periphery of the segment 21 is not concentric with the axis 8, but is so shaped as to depress the chain 20 as well as wind or bend the chain over the periphery of the segment. Rigid with the segment 21 is an arm 22 which extends approximately diametrically opposite to the segment 21 and is connected by means of a chain or other suitable flexible connection 23 with a lug 24 on a bell crank 25 fixed to a shaft 26 which is rotatably mounted upon the tongue 1^a. The bell crank 25 has a segmental winding portion 27 over which the chain 23 is bent as the bell crank is swung upwardly. Normally the lug 24 and the winding portion 27 extend forwardly from the axis 26 of the bell crank 25. The bell crank 25 comprises a forwardly and upwardly extending portion which is connected at 28 to a hand lever 29 by means of a link 30, said hand lever being pivotally mounted upon the main frame 1 rearwardly of the bell crank 25. Referring to Fig. 1: When the finger bar is in operative position, the point 24 is in approximately the horizontal plane of the axis 26 so that turning movement of the bell crank 25 will cause the finger bar to be quickly raised. The point 28 is so lo-

cated with reference to the axis 26 that the hand lever 29 has efficient leverage on the bell crank in raising the latter. It is desired, 5 position in any ordinary or suitable manner, as, for example, by means of a detent 31 engaging a locking segment 32.

A coiled tension spring 33 is attached at one end to a pin 34 on the winding segment 21. The other end of the spring is connected to a rod 35 which extends slidably through a lug 36 on the bar 6. 37 is a nut turned on the screw-threaded end of the rod 35 and bearing against the lug 36. The 15 spring 33 serves to counterbalance a portion of the weight of the finger bar and the parts supported by said bar. The finger bar is further counterbalanced by means of a coiled tension spring 38 connected at one end to 20 an arm 39 fixed to the shaft 26 and at its other end to a lug 40 on the main frame 1. By properly adjusting the nut 37 the springs 33 and 38 will counterbalance the finger bar to such an extent that said bar will simply 25 float over the ground. The finger bar is thus prevented from dragging upon the ground whereby side draft is avoided, and the power necessary to pull the finger bar along the ground is saved. By reason of 30 the employment of the winding segments 21 and 26, the finger bar may be lifted from its operative position to an approximately vertical position without an inconvenient amount of movement of the hand lever 29, 35 the counterbalancing of the finger bar being preserved throughout the lifting movement.

It will be apparent from Fig. 1 that the lug 12 is of such length that the pushing bar 7 of the secondary frame extends substantially horizontally. Resistance to the 40 advance of the cutting mechanism acting through the push rod 7 therefore has no tendency to lift the wheels from the ground and thus reduce their traction.

45 The shaft 26 is journaled in a plate 41 which is mounted on the tongue 1^a. To provide a firm and durable seat for the plate 41, I place upon the tongue 1^a two angle irons 42 fitting over the upper corners of the tongue and extending longitudinally thereof. The angle irons 42 may be secured to the tongue 1^a in any suitable manner, as, for example, by means of screws 43. The plate 41 is seated directly upon the angle irons 42 and is secured in place by means of a U-bolt or shackle 44 that extends from one corner of the plate 41 down around the tongue and up to the diagonally-opposite corner of the plate. To assist in 55 preventing the plate 41 from sliding along the tongue suitable means may be provided, as, for example, two studs 45 extending downwardly from the plate 41 into holes in the angle irons 42. To keep the plate 41 60 from twisting on the tongue, the two cor-

ners opposite to those engaged by the U-bolt 44 are provided with downwardly-extending lugs 46 that bear against the angle irons 42.

A cam 47 on the hand lever 29 is arranged to engage a rocker arm 48 on the 70 main frame to throw out the clutch (not shown) when the finger bar has reached a degree of elevation rendering any further operation of the cutting mechanism impractical.

75 The draft connection may be of any suitable character. The preferred construction comprises a draw-bar 49 connected at its rear end to a lug 50 on the lower side of the tongue 1^a relatively near the axle. The 80 doubletree or other draft appliance is connected to the forward end of the draw-bar 49. Said draw-bar is supported near its forward end by means of a strap or loop 51 depending from the tongue 1^a.

85 I claim as my invention:

1. A mower having, in combination, a main frame, a tongue secured to the main frame, a secondary frame comprising a front bar pivoted to the main frame, a push bar 90 pivoted to the main frame and rigidly connected to the front bar, and a brace bar rigidly connected to the front bar and the push bar and extending forwardly of the front bar, a yoke mounted on the front bar 95 and having a forward arm and a rear arm, a shoe pivoted to said arms, a finger bar rigidly connected to the shoe, an arm extending upwardly from the shoe forward of the front arm of the yoke, a winding segment pivoted upon the forward end of the brace bar in front of the front bar and extending toward the shoe, a flexible connection attached at one end to the upwardly extending arm and at its other end to the 105 lower side of the winding segment, an arm fixed to the winding segment and extending substantially opposite to the segment, a bell crank pivotally mounted upon the tongue and having a portion which normally extends forwardly of the axis of the bell crank, a flexible connection between said 110 forwardly extending portion of the bell crank and the arm attached to the winding segment, a hand lever pivoted on the main frame, said bell crank having a portion which normally extends upwardly and forwardly of the axis of the bell crank, and a connection between the hand lever and said upwardly and forwardly extending portion 115 of the bell crank.

120 2. A mower having, in combination, a main frame, a tongue secured to the main frame, a secondary frame comprising a front bar and a push bar pivoted to the main frame 125 and rigidly connected together, a yoke mounted on the front bar and having a forward arm and a rear arm, a shoe pivoted to said arms, a finger bar rigidly connected to the shoe, an arm extending upwardly from 130

- the shoe forward of the front arm of the yoke, a winding segment pivoted upon the secondary frame in front of the front bar and extending toward the shoe, a flexible connection attached at one end to the upwardly extending arm and at its other end to the lower side of the winding segment, an arm fixed to the winding segment and extending substantially opposite to the segment, a bell crank pivotally mounted upon the tongue and having a portion which normally extends forwardly of the axis of the bell crank, a flexible connection between said forwardly extending portion of the bell crank and the arm attached to the winding segment, a hand lever pivoted on the main frame rearwardly of the bell crank, said bell crank having a portion which normally extends upwardly and forwardly of the axis of the bell crank, and a connection between the hand lever and said upwardly and forwardly extending portion of the bell crank.
3. A mower having, in combination, a main frame, a tongue secured to the main frame, a secondary frame comprising a front bar and a push bar pivoted to the main frame and rigidly connected together, a yoke mounted on the front bar and having a forward arm and a rear arm, a shoe pivoted to said arms, a finger bar rigidly connected to the shoe, an arm extending upwardly from the shoe forward of the front arm of the yoke, a winding segment pivoted upon the secondary frame in front of the front bar and extending toward the shoe, a flexible connection attached at one end to the upwardly extending arm and at its other end to the lower side of the winding segment, an arm fixed to the winding segment and extending substantially opposite to the segment, a bell crank pivotally mounted upon the tongue and having a portion which normally extends forwardly of the axis of the bell crank, a flexible connection between said forwardly extending portion of the bell crank and the arm attached to the winding segment, a lever pivoted on the main frame, and a connection between the lever and the bell crank.
5. A mower having, in combination, a main frame, a secondary frame swingingly connected to the main frame, a finger bar pivoted to the secondary frame, a winding segment pivoted on the secondary frame and extending toward the finger bar, an arm fixed to the segment and extending in substantially the opposite direction, a flexible connection between the winding segment and the finger bar, a bell crank pivoted on the main frame, a flexible connection between the winding segment and the bell crank, a lever on the main frame and connected to the bell crank for lifting the latter, a spring connected to the bell crank, and a spring connected to the winding segment, said springs coöperating to counterbalance the finger bar.
6. A mower having, in combination, a main frame, a secondary frame swingingly connected to the main frame, a finger bar pivoted to the secondary frame, a winding segment pivoted on one of said frames and extending toward the finger bar, an arm fixed to the segment and extending in substantially the opposite direction, a flexible connection between said arm and the finger bar, a bell crank pivotally mounted upon the tongue and having a portion which normally extends forwardly of the axis of the bell crank, a flexible connection between the winding segment and the bell crank, a lever on the main frame and connected to the bell crank for lifting the latter, a spring connected to the bell crank, and a spring connected to the winding segment, said springs coöperating to counterbalance the finger bar.
7. A mower having, in combination, a main frame comprising a tubular portion, an axle extending through said portion, a secondary frame comprising a front bar and a push bar, the stubbleward end of the front bar being movably connected to the main frame, the grassward end of the front bar being connected to the forward end of the push bar, a lug extending downwardly from said tubular portion of the main frame, the rear end of the push bar being pivoted to said lug, said push bar extending approximately horizontally when the secondary frame is in operative position.
8. A mower having, in combination, a main frame, a secondary frame comprising a front bar and a push bar, the stubbleward end of the front bar being movably connected to the main frame, the grassward end of the front bar being connected to the forward end of the push bar, a lug extending downwardly from the main frame, the rear end of the push bar being pivoted to said lug, said push bar extending approximately horizontally when the secondary frame is in operative position.
9. A mower having, in combination, a main frame, a secondary frame swingingly connected to the main frame, the secondary frame comprising a front bar and a push bar, a member connecting the grassward end of the front bar to the forward end of the push bar, and a yoke pivoted upon the front bar at opposite sides of said connecting member.
10. A mower having, in combination, a main frame, a secondary frame swingingly connected to the main frame, the secondary frame comprising a front bar and another bar, a member connecting said bars, and a yoke pivotally supported upon the grassward end of the front bar, said yoke having an opening through which said member extends.

11. A mower having, in combination, a main frame, a secondary frame swingingly connected to the main frame, the secondary frame comprising a front bar and another bar, a member connecting said bars, and a yoke pivotally supported upon the grassward end of the front bar, said yoke having an opening through which said member extends.
12. A mower having, in combination, a main frame, a secondary frame swingingly connected to the main frame, the secondary frame comprising a front bar and another bar, a member connecting said bars, and a yoke pivotally supported upon the grassward end of the front bar, said yoke having an opening through which said member extends.
13. A mower having, in combination, a main frame, a secondary frame swingingly connected to the main frame, the secondary frame comprising a front bar and another bar, a member connecting said bars, and a yoke pivotally supported upon the grassward end of the front bar, said yoke having an opening through which said member extends.

10. A mower having, in combination, a tongue, angle irons fitting over the corners of said tongue and extending longitudinally thereof, a plate seated on said angle irons, 5 a U-bolt engaging diagonally-opposite corners of said plate and extending around the tongue, lugs on the other two corners of the plate extending downwardly beside said angle irons, and studs on said plate extending 10 into openings in said angle irons to prevent sliding of the plate along the tongue.
11. A mower having, in combination, a tongue, angle irons fitting over the corners of said tongue and extending longitudinally thereof, 15 a plate seated on said angle irons, a U-bolt engaging said plate and extending around the tongue, and means to prevent the plate from turning on said angle irons.
12. A mower having, in combination, a tongue, angle irons fitting over the corners of said tongue and extending longitudinally thereof, 20 a plate seated on said angle irons, portions extending downwardly from said plate at opposite sides of said tongue to engage the angle irons and prevent turning of the plate, and a U-bolt engaging said plate and extending around the tongue.
13. A mower having, in combination, a tongue, a plate, a U-bolt engaging said plate and extending around the tongue, and means 25 to prevent the plate from turning with reference to the tongue.
14. A mower having, in combination, a main frame, a secondary frame, a yoke 30 mounted on the secondary frame, a shoe

pivoted to the yoke, an arm extending upwardly from the shoe, a winding segment pivoted upon the secondary frame and extending toward the shoe, a flexible connection attached at one end to the arm and at 40 its other end to the lower side of the winding segment, an arm fixed to the winding segment and extending substantially opposite to the segment, a bell crank pivotally supported with reference to the main frame, 45 a flexible connection between said bell crank and the second mentioned arm, a lever on the main frame, and a connection between the lever and said bell crank for swinging the bell crank to pull the first mentioned 50 flexible connection down below the axis of the winding segment.

15. A mower having, in combination, a main frame, a front bar pivoted to the main frame, a push bar pivoted to the main frame, 55 a bracket rigidly uniting the forward end of the push bar and the grassward end of the front bar, a brace bar connected at its rear end to the push bar, a bracket connecting the forward portion of the brace 60 bar to the front bar, and a yoke having a sleeve rotatably mounted upon the grassward end of the front bar, said sleeve having an opening therein through which the first mentioned bracket projects, the stubble- 65 ward end of said sleeve lying between said brackets.

In testimony whereof I have hereunto set my hand.

JOHN C. BOHMKER.
